LIGHTING FIXTURE

Albert L. Arenberg, Highland Park, Ill., assignor
to Patent License Corporation, Chicago, Ill., a
corporation of Illinois

Application February 15, 1937, Serial No. 125,716

1 Claim. (Cl. 240—7.35)

The present invention is concerned with lighting fixtures of the type used along the ceilings of railway cars and other vehicles.

The object of the invention is to provide an improved fixture in which a row of bulbs arranged along a ventilating opening at the center of the ceiling of a car is screened from the vision of the passengers by a unique baffle structure which redirects the light from the bulbs to the ceiling and at the same time distributes conditioned air entering through the opening.

This improved fixture is characterized by a horizontal baffle strip of laterally tapering cross section which is centered beneath the bulbs and is formed in two horizontally separated sections, with the opening between the sections located directly below the bulbs. The fixture also includes another horizontal baffle strip which is quite a bit narrower than the sections of the upper strip and is centered beneath the opening in the latter in vertically spaced relation thereto. The spacing of the bulbs, the curvature of the reflecting surfaces of the baffle strips, and the size and arrangement of the strips are all so related as to produce an even light on the ceiling, without glare.

Other more specific objects and advantages of the invention will be evident to those skilled in the art upon a full understanding of the construction, arrangement and function of the parts entering into the complete fixture.

One form of the invention is presented herein by way of illustration, but it will of course be appreciated that the invention may be embodied in other structurally modified forms coming equally within the scope of the appended claim.

In the accompanying drawing:

Fig. 1 is a schematic sectional view through the upper portion of a railway car, showing the new fixture, and the cut-off and reflecting angles provided by the same;

Fig. 2 is a vertical transverse section through the fixture and ceiling;

Fig. 3 is a vertical longitudinal section through the ceiling, looking toward one side of the fixture; and

Fig. 4 is a vertical transverse section through one edge of the fixture, showing an upstanding baffle strip added to the edge as an alternative construction.

The fixture shown in the drawing is adapted to be applied to the ceiling 10 of a railway car or other vehicle beneath a row of bulbs 11 positioned at regular intervals along a ventilation opening 12 formed in the ceiling. The opening

12 communicates with a space 13 above the ceiling, which space constitutes a conduit in the air-conditioning system of the car.

The fixture is characterized by a wide baffle strip 14 which is composed of two laterally separated sections 15, and a narrow baffle strip 16 which is positioned beneath the opening 17 between the sections 15. The sections 15 are identical in size and shape and are of hollow sheet metal construction. Their lower surfaces 18 are horizontal, while their upper surfaces 19, which are finished as reflectors, slope downwardly in opposite directions from points 20 located adjacent the opening 17, the inclination outwardly from the points 20 being very gradual, and the inclination inwardly from those points being quite abrupt. The baffle strip 16 is likewise of hollow construction. Its lower surface 21 is convex, while its upper surface 22, which is finished as a reflector, slopes downwardly in opposite directions from the center, the surface 22 being somewhat concave between the center and edges of the strip.

The baffle strips 14 and 16 are supported at regular intervals from suspension brackets 23. The sections 15 of the baffle strip 14 are attached by screws 24 to laterally extending wing-like arms 25 on the brackets, while the baffle strip 16 is attached by bolts 26 to downwardly projecting formations 27 at the centers of the brackets.

The upper baffle strip 14 is so arranged and proportioned with respect to the ceiling 10 and bulbs 11 as to cut off all direct rays from the bulbs above the heads of the passengers in the car, and the reflecting surfaces 19 of the upper baffle strip are so disposed with respect to those elements as to reflect certain of the rays back onto the ceiling, providing an even distribution of light from one side of the ceiling to the other, without glare, all as indicated schematically with arrows in Fig. 1. The upper baffle strip 14 also functions in much the same way with currents of air entering through the opening 12, the air being uniformly distributed across the upper portion of the car above the heads of the passengers without the formation of any objectionable drafts. The lower baffle strip 16 produces a lateral spread of light rays, by reflection, against the under sides of the laterally projecting sections of the upper baffle strip, softly illuminating the latter. This lower baffle strip also functions as a secondary distributor head for the air, deflecting laterally the air which passes downwardly through the opening 17 present between the two sections of the upper baffle strip.

In Fig. 4 an upstanding flange 28 is shown attached to one of the side edges of the upper baffle strip 14. Supplemental flanges of this character may be used to advantage in those installations wherein either the width of the upper baffle strip or its spacing from the bulbs is such as to bring portions of the bulbs within the vision of some of the passengers.

While the opening 12 in the ceiling has been represented throughout this description as the inlet for the conditioned air, it will of course be appreciated that the inlet may assume any one of a great variety of forms, depending upon the structure of the ceiling and the general design of the car.

As will be noted in Fig. 1, the outer side edges of the fixture are preferably so located with respect to the ceiling and bulbs as to cause the direct ray cut-off lines 29 to fall at ordinarily concealed points about even with the rear edges of the luggage racks 30, which location of whatever shadows may be cast by the edges of the fixture effectively eliminates any suggestion of shadowing on the side walls. The reading areas about the seats 31 may advantageously be illuminated by supplemental lighting units 32 of

any suitable construction built into the under sides of the luggage racks along the edges thereof.

I claim:

5 In combination with the ceiling structure of a passenger vehicle, a plurality of spaced parallel channels extending longitudinally of said ceiling defining a central recessed ventilating duct, a row of lights mounted in said ventilating duct, a 10 lighting fixture and air baffle below said duct, said fixture comprising three baffle strips, two of which are identical with each other in size and shape and are arranged symmetrically with respect to the longitudinal axis of the fixture in laterally separated relation to each other, with the 15 gap between the same centered directly below the bulbs, and the third of which baffle strips is spaced below the first two baffle strips directly under the gap, with the outer edges of the third 20 strip lapping the inner edges of the first two strips far enough to cut off any direct rays from the bulbs, and brackets of inverted T-shape positioned at intervals along the baffle strips in vertical transverse planes between certain of the 25 bulbs for supporting the fixture.

ALBERT L. ARENBERG.
